UNITED STATES PATENT OFFICE

GASTON CANDAS, OF PARIS, FRANCE

BROOCH AND THE LIKE

Application filed May 31, 1930. Serial No. 457,914.

This invention relates to improvements in articles of jewelry, brooches, lockets, shoe-buckles and the like and has for its principal objects the provision of a simple, durable and 5 cheap construction which lends itself to the production of a wide variety of designs without necessitating the employment of a different base or support for each different design.

10 The invention is fully set forth and described in the following description and drawings forming part thereof in which

Figure 1 is a front elevation of a brooch embodying my invention, the same being partially broken away to show a portion of the frame;

Fig. 2 is a rear elevation of such brooch;

Fig. 3 is a vertical section on the line 3—3 of Fig. 1, except that the construction shown 20 in Fig. 1 is not broken away when taking such section;

Fig. 4 is an elevation of the frame of such brooch isolated;

Fig. 5 is a plan view of the frame shown 25 in Fig. 4;

Fig. 6 is an elevation of one of the ornamental clasp members;

Fig. 7 is a plan view of such clasp member in an open position and

20 Fig. 8 is a vertical section on the line 8—8 of Fig. 7.

Referring to the drawing, a skeleton frame is provided that consists of top and bottom cap plates 1 to which are secured by 25 brazing, soldering or the like, the inner ends of rectangular sections comprising inner transverse bars 2, longitudinal bars 3 and outer transverse bars 4, the latter being provided with inwardly projecting integral 40 slotted lugs 5, the same functioning as hereinafter described. A pin member 6, which is pivoted to the lug 7 that project from the rear of one of said sections is adapted to be secured by a catch member 8 and thereby 45 serves, when closed, to retain the frame on the garment of a wearer.

Said skeleton frame, which may be either built up as herein described or may be stamped out or otherwise formed in an integral piece, is adapted to receive similar orna-

mental clasp members. The latter comprise cover elements 9, 9' having vertical rear lugs 10, 10', abutting rear extensions 11, 11' and claw-shaped lugs 12, 12' respectively, the latter functioning as hereinafter described. 55 Bottom or base elements 13, 13' are hinged to the respective cover elements 9, 9' and each of said base elements is provided with leaf spring members 14, 14', the rear faces of which respectively engage the shoulders *a* 60 formed on the lugs 10, 10' when the clasp is open and the top face *b* of such lugs when the clasp is closed thereby serving to either positively maintain the clasp in an open position when deliberately opened or in a closed position when the clasp is deliberately closed. 65 Terminal lugs 15, 15' are adapted to project across the outer ends of the elements 9, 9' respectively when the clasp is closed. Barbs 16, 16' are provided on the inner faces of the 70 elements 13, 13' in order to secure the frame to a shoe upper or the like and one of said barbs on each element is adapted to register with and project into the slots in the respective opposing lugs 5 whereby the clasp members are more effectively located and prevented from lateral shifting once the same 75 are mounted on the skeleton frame in the manner hereinafter described. Said elements 13, 13' are also provided with claw-like lugs 17, 17' respectively which are adapted to respectively co-operate with the lugs 12, 12' and snugly embrace the bars 2 of the opposing sections of the frame when the clasps are clamped on the frame in the position shown 80 in Figs. 1 to 3.

In assembling the brooch, the lower member 13' of one of the clasps is first inserted from below upwardly through the central opening in the base or frame which is formed between opposing bars 2 and then such clasp member is adjusted until it is in the position shown in full lines at the right of Fig. 3, whereupon the two halves of the clasp member are closed so that the lower half 13 90 assumes the dotted line position at the right of Fig. 3. Thereupon the other clasp member is similarly applied to the frame with the result that a brooch similar to that illustrated in Figs. 1 and 2 is produced. When prop- 95 100

erly assembled the lugs 11, 11' on each of the elements 9, 9' will abut against each other and form an almost invisible joint and the cover elements, 9, 9' will effectively co-operate with the cap plates to conceal the skeleton frame of the support.

Obviously the cover members are intended to receive suitable ornamentation as engraving, jewel settings, or inlays and thereby a wide variety of ornamental effects can be obtained while employing a skeleton frame of standard construction. Furthermore, clasps of different empirical design and differing ornamentation can be supplied with a single frame thereby admitting of the wearer completely changing the effect produced, the same as if the entire article were replaced.

As is evident from the foregoing description, my improved device is sturdy of construction, easily changed to produce an entirely different appearance or effect and withal is extremely cheap and simple to assemble.

Various changes from the preferred construction herein set forth and within the scope of the appended claims may be made without departing from the spirit of my invention.

Having thus described my invention, what I claim and desire to obtain by United States Letters Patent is:—

1. In an article of jewelry, the combination comprising a skeleton frame having an aperture on opposite sides thereof for the reception of clasp members and clasp members adapted to embrace portions of said frame, and to effectually conceal said apertures when mounted on said frame, said clasp members being provided with means for rigidly securing the same to said frame.

2. In an article of jewelry, the combination comprising a skeleton frame having opposing apertures, apertured lugs projecting inwardly from the outer edges of each aperture respectively, clasp members adapted to be mounted on said frame and to substantially conceal said apertures when so mounted thereon and means including spike members adapted to project through the respective apertures in said lugs for rigidly securing and positioning such clasp members on said frame.

3. In an article of jewelry, the combination comprising a skeleton support having a central aperture and lateral apertures disposed on said opposite sides of said central aperture, clasp members having opposing hands, at least one of which is adapted to pass completely through the central aperture so as to permit of the positioning of such clasp member upon said frame so that one-half extends along one side thereof and the other half of such clasp member along the reverse side of said frame and means carried by said clasp member for effectively securing said clasp members to said frame when the same

are so positioned that said lateral apertures are substantially covered thereby.

4. In an article of jewelry, the combination comprising a skeleton frame having a central aperture and opposing lateral apertures adjacent said central apertures, transverse bar members constituting the margins of such lateral apertures, inwardly extending lugs integral with the outer bars of said lateral apertures, clasp members, each comprising two halves hinged together, at least one of said halves being adapted to be inserted and project through the central apertures in said frame, elastic means for maintaining said clasp members in a closed position when once closed, or in an open position when open and means carried by said clasp members for rigidly securing the same to said frame when such clasp members are fitted thereto, so that one-half projects across one-half of said frame and the other half of said clasp member across the reverse side of said frame.

5. In an article of jewelry, the sub-combination comprising a clasp member consisting of two halves hinged together, elastic means for normally holding such clasp member when closed in a closed position or when open, in an open position and claw-like members adapted to effectively grip a bar of a supporting frame when such clasp members are mounted thereon.

Signed at New York, in the county and State of New York, this 29th day of May, 1930.
